PUMP

Lindsay H. Browne, Weston, Conn., assignor to
 American Brake Shoe Company, Wilmington,
 Del., a corporation of Delaware

Application August 21, 1947, Serial No. 769,883

9 Claims. (Cl. 103—150)

1

This invention relates to pumps and more specifically to double-acting membrane pumps wherein the membranes are actuated by differential fluid pressure.

A primary object of my invention is to enable liquids which are considered relatively difficult to handle, such as for example, gritty water and the like, to be pumped in a novel and expeditious manner.

A further object is to construct a novel double-acting membrane pump wherein, under the control of a shuttle valve, working fluid is selectively fed by a gear pump to one or the other of two chambers to actuate distensible membranes therein.

Another object of my invention is to automatically effect shifting of the aforesaid shuttle valve, in a novel and expeditious manner, upon actuation of the membranes to thereby cause the pump to feed working fluid to one and then the other membrane alternately.

A further object of my invention is to construct a novel hydraulically operated membrane pump wherein the pressure of the working fluid is determined by the pressure of the liquid being pumped, and high pressures may be used therein with little deleterious effect on the membrane of the pump.

Yet another object of my invention is to enable the construction of a compact membrane pump of relatively large capacity, and capable of producing a substantially constant flow of liquid, wherein the membranes thereof are actuated relatively slowly, and subjected to relatively little flexure.

A further object of my invention is to construct a membrane pump wherein an oil pump which operates in a closed circuit furnishes working fluid under pressure for actuating the membranes.

Another object is to construct a membrane pump of the aforesaid type in such a manner that the oil pump thereof may be submerged in oil during the operation of the membrane pump.

Another object of my invention is to construct a novel membrane pump of the previously mentioned type wherein the oil pump and other mechanisms thereof which require lubrication are automatically self-lubricated during the operation of the membrane pump.

Other and further objects of the present invention will be apparent from the following description and claims and are illustrated in the accompanying drawings which, by way of illustration, show a preferred embodiment and the

2

principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims.

- 10 In the drawings:
 Fig. 1 is a longitudinal sectional view taken substantially vertically through a pump embodying my invention;
 Fig. 2 is a transverse sectional view taken substantially along the line 2—2 in Fig. 1;
 Fig. 3 is a partially sectional view taken substantially along the line 3—3 in Fig. 4;
 Fig. 4 is a sectional view taken substantially along the line 4—4 in Fig. 3;
 20 Fig. 5 is a rear elevational view of the pump shown in Fig. 2, looking in the direction opposite to that in which the pump is viewed in Fig. 2; and
 Fig. 6 is a detail sectional view taken substantially along the line 6—6 in Fig. 4.

General

The pump 20, shown in the accompanying drawings to illustrate the principles of my invention, embodies in general, a housing 22, two distensible membranes 24 and 25 adapted, upon distention back and forth, to pump liquid into and out of chambers 27 and 28 formed between the housing 22 and two end plates 30 and 31, respectively, mounted thereon, a gear pump 33 for pumping oil or other suitable working fluid to the membranes 24 and 25 to actuate the latter, an actuator valve 35 for selectively controlling the flow of oil from the gear pump 33 to the membranes 24 and 25, and a selector valve 37 for controlling the operation of the actuator valve 35 in accordance with the operative positions of the membranes 24 and 25.

Construction of the pump 20

- 45 The housing 22 of my novel pump 20 is substantially cylindrical in shape and, as best shown in Figs. 1 and 3, comprises a front wall 41, a top wall 42, a rear wall 43, a bottom wall 44, two end walls 45 and 46, and a supporting base 47 projecting downwardly from the bottom wall 44. An inspection plate 49 is attached by suitable means such as bolts 50 to the front wall 41, in position to cover a hand hole or opening 52, Fig. 2, formed in the front wall 41, and a cover plate 54 is attached by bolts 55 to the rear wall 43 in position

to cover an opening 57 formed in the latter. The top wall 42 and the bottom wall 44 have passageways 59 and 60, respectively, extending substantially longitudinally therethrough. Two passageways 62 and 63 extend from openings formed in the front portions of the top wall 42 and bottom wall 44, respectively, into communication with the passageways 59 and 60 intermediate the ends thereof.

The two end plates 30 and 31 are attached to the opposite end portions of the housing 22 by suitable means such as wing-nuts 68 and bolts 69, Figs. 3, 4 and 5. The end plates 30 and 31 and the end walls 45 and 46 are shaped so as to form the aforementioned chambers 27 and 28, Figs. 1 and 4, when the end plates are properly mounted on the housing 22.

The end plate 30 has two passageways 71 and 72 formed therein, the passageway 71 having one end in communication with the chamber 27 and the other end in communication with the passageway 59 in the housing 22, and the passageway 72 having one end in communication with the chamber 27 and the other end in communication with the passageway 60. Likewise, the end plate 32 has two passageways 74 and 75 formed therein which interconnect the chamber 28 with the passageways 59 and 60, respectively.

Two valve cages 77 and 78 are mounted in the passageways 71 and 74, respectively, in engagement with shoulders 81 and 82 formed therein and are held in such position by suitable means such as snap-rings 83 and 84. The valve cages 77 and 78 are of an open frame-work construction and each has a ball check-valve 86 and 87, respectively, mounted therein and yieldingly urged into engagement with a valve seat 89 and 90 by a compression spring 92 and 93, respectively, the ball check-valves 86 and 87 being effective to close the passageways 71 and 74, when seated on the valve seats 89 and 90.

Two valve cages 95 and 96 are also mounted in the passageways 72 and 75 and are held in engagement with shoulders 98 and 99 therein by snap-rings 101 and 102. The valve cages 95 and 96 are likewise of an open frame-work construction and have valve seats 104 and 105 formed therein against which ball check-valves 107 and 108 are yieldingly urged by springs 110 and 111 mounted within the passageways 72 and 75, the ball check-valves 107 and 108 being effective to close the passageways 72 and 75 when seated on the valve seats 104 and 105.

Each of the valve cages 77, 78, 95 and 96 has sealing rings 113 mounted in grooves formed therein and engaged with the sidewalls of the respective passageways 71, 74, 72 and 75 to prevent leakage of fluid around the cages within the passageways during operation of my pump, the sealing rings 113 being made of any suitable material such as, for example, a chlorobutadiene polymer ("neoprene").

From the foregoing it will be apparent to those skilled in the art that inlet passages to those portions of the chambers 27 and 28 outside of the distensible membranes 24 and 25, are provided through the passageways 63, 60 and 72, and through the passageways 63, 60 and 75, respectively, the outer end portion of the passageway 63 having screw threads 115 formed thereon for readily connecting a suitable intake coupling thereto. Also, it will be apparent that outlet passages from those portions of the chambers 27 and 28 outside of the distensible members 24 and 25 are provided through the passageways 62, 75

59 and 71, and the passageways 62, 59, and 74, respectively, the outer end portion of the passageway 62 having screw threads 116 formed thereon for readily connecting a suitable outlet coupling thereto.

The distensible membranes 24 and 25 are connected by nuts 118 and 119 and nuts 121 and 122, respectively, to opposite end portions of a valve rod 124 slidably mounted within a passageway 126, formed in the selector valve 37, in close-fitting engagement with the side walls thereof, suitable sealing rings 127 being mounted in the side walls of the passageway 126 at both ends thereof and engaged with the rod 124 to prevent leakage of fluid therebetween. The valve rod 124 extends through suitable openings 128 and 129 formed in the end plates 45 and 46 of the housing 22, and sealing rings 131, made of suitable material such as chlorobutadiene polymer, are mounted in grooves in the side walls of the openings to seal against leakage of fluid through the openings past the rod 124.

The housing 133 of the selector valve 37 is mounted within the housing 22 substantially mid-way between bosses 135 and 136, Figs. 1 and 4, formed in the end walls 45 and 46, positioning of the housing between the bosses 135 and 136 being effected by two bolts 138 and 139, Fig. 1, screwed into tapped openings formed in opposite end portions of the housing 133 and engaged with the bosses 135 and 136 respectively. Lock-nuts 141 and 142 are mounted on the bolts 138 and 139 to hold the bolts in adjusted position. The housing 133 of the selector valve 37 is separable into two parts 133a and 133b, Fig. 1, and a bolt 144 screwed into the part 133b and engageable with the part 133a is effective to adjust the longitudinal position of these parts relative to each other.

40 The part 133a of the housing 133 has a passageway 146, Fig. 4, formed therein, one end of which opens into the housing 22 and the other end of which interconnects with one end of a passageway 148. The other end of the passageway 148 interconnects with one end of each of two passageways 150 and 151, the other ends of the passageways 150 and 151 having openings in which suitable coupling members 153 and 154, respectively, attached to one end portion of tubes 156 and 157, respectively, Figs. 1 and 4, may be connected for purposes to be discussed in greater detail presently.

Likewise, the part 133b of the housing 133 has a passageway 159 formed therein, one end of which opens into the housing 22 and the other end of which interconnects with one end of a passageway 161. The other end of the passageway 161 interconnects with one end of each of two passageways 163 and 164, the other ends of the passageways 163 and 164, having openings in which suitable coupling members 166 and 167, respectively, attached to one end portion of tubes 169 and 170, may be connected.

65 The end portions of the tubes 156 and 169 opposite to the end portions to which the coupling members 153 and 166 are attached, are connected to the chambers 27 and 28 by coupling members 168 and 171 so that the passageways 150 and 163 in the selector valve 37 are connected to the respective chambers 27 and 28.

The valve rod 124 in the selector valve 37 has two radial grooves 172 and 173, Fig. 4, formed therein, the groove 172 being adapted to reciprocate between alignment with the passages 146 and 150 upon reciprocation of the rod 124, by

movement of the distensible membranes 24 and 25 back and forth within the chambers 27 and 28, as will be discussed in greater detail hereinafter, and the groove 173 being adapted to reciprocate between alignment with the passages 159 and 163 upon such reciprocation of the rod 124.

The actuator valve 35 includes a housing 54 attached to the inner face of the cover plate 54 on the housing 22 by suitable means such as bolts 177, Fig. 3. The housing 175 has a passageway 179 extending substantially longitudinally therethrough and the ends of which are closed by suitable plugs 181 and 182.

A plurality of passageways 184, 185, 186, 187, 188, 189 and 190, Fig. 4, extend transversely through the housing 175 from the passageway 179; the passageway 184 having threads tapped therein for connection to a coupling member 192 on the end of the tube 157, opposite the end to which the coupling member 154 is connected; the passageway 185 opening downwardly, Fig. 6, into the housing 22; the passageway 186 interconnecting with one end portion of a passageway 194 which extends through one end portion of the cover plate 54 and the other end of which is connected by a passageway 196, extending through the end wall 45, to the chamber 27 inwardly of the distensible membrane 24; the passageway 187 interconnecting with the upper end portion of a passageway 198 which extends vertically through a portion of the cover plate 54, Figs. 2, 4 and 5; the passageway 188 interconnecting with an end portion of a passageway 200 which extends through the other portion of the cover plate 54, opposite to that in which the passageway 196 is located, and is connected by a passageway 202 in the end wall 46 to the chamber 28; the passageway 189 opening downwardly into the housing 22 in a manner similar to that hereinbefore discussed with respect to the passageway 185; and the passageway 190 having threads tapped therein by which a coupling member 204, on the end of the tube 170 opposite the end to which the coupling member 167 is attached, may be connected to the passageway 190.

A valve rod 206, having valve heads 208 and 209 formed thereon, is slidably mounted within the passageway 179 in the actuator-valve housing 175 with the heads 208 and 209 in close fitting engagement with the sidewalls of the passageway 179. As is best seen in Fig. 4, the valve heads 208 and 209 are so positioned on the valve rod that when the rod 206 occupies the position shown in Fig. 4, wherein it is displaced to full extent in one direction in the passageway 179, the valve head 208 is positioned between the passageways 185 and 186 to seal the passageway 179 therebetween, and the valve head 209 is positioned between the passageways 187 and 188 to seal the passageway 179 therebetween. Likewise, it will be apparent to those skilled in the art that when the valve rod is displaced to full extent in the opposite direction in the passageway 179 (that is, to the right as viewed in Fig. 4), the valve head 208 will then be positioned between the passageways 186 and 187 and the valve head 209 will be positioned between the passageways 188 and 189. The operation of my novel pump is controlled by shifting the valve rod 206 back and forth between these two positions in the passageway 179, as will be discussed in greater detail hereinafter.

Two sealing rings 211 and 212 are mounted in grooves formed in the opposite end portions of

the side walls of the passageway 179 to seal against leakage of fluid within the passageway past the valve rod 206 between the passageways 184 and 185, and between the passageways 189 and 190, respectively.

A passageway 214, Fig. 2, is formed in the lower end portion of the rear wall 43 of the housing 22 and interconnects with the lower end portion of a substantially vertically extending passageway 216, Figs. 2 and 5, formed in the cover plate 54. The upper end portion of the passageway 216 is in communication through an opening 217 with the intake side of the oil pump 33, Fig. 2, and the pressure side, or outlet side of the oil pump 33 is in communication through an opening 220 with the lower end portion of the passageway 198 which it will be remembered is connected to the passageway 187 in the actuator valve 35. When my novel pump is in operation, it is desirable that the housing 22 be filled with oil to a level sufficiently high to cover the pump 33. Therefore, it will be seen that a supply of oil is always available within the housing 22 to be fed through the passageways 214 and 216 into the pump 33.

The pump 33, shown in the accompanying drawings, is of the type commonly known as a gear-type pump and embodies a driving gear 218 and a driven gear 219, Fig. 5. The gear 218 is fastened on a shaft 221 which is journaled in suitable bearings and projects outwardly through an opening 223 in the cover plate 54, the outwardly projected end portion of the shaft 221 being adapted to be coupled to a suitable motor or other type of prime mover, not shown, for driving the gears 218 and 219, as will be apparent to those skilled in the art.

A pressure relief valve 225 of the diaphragm type has an inlet passageway 227 connected by a passageway 228 in the cover plate 54 to the oil passageway 198, on the pressure side of the pump 33, and has an outlet passageway 230 connected to a passageway 232 opening into the housing 22 and extending transversely through the cover plate 54. A ball check-valve 234 is normally held by a compression spring 236 in effective position to close the connection between the inlet passageway 227 and the outlet passageway 230 of the relief valve 225 and thereby prevent feeding of oil from the pump 33 through the valve 225 and back into the housing 22. However, when the pressure of the oil discharged into the passageway 198 rises above a predetermined pressure, the resulting force applied to the diaphragm 238 thereof is effective to unseat the ball 234 and thereby relieve the pressure in the passageway 198 by opening the connecting passageways 227 and 230 therefrom back to the interior of the housing 22.

From the foregoing it will be seen that the gear pump 33, the chambers 27 and 28, the actuator valve 35 and the selector valve 37 are all operatively interconnected. By this interconnection, the gear pump 33 is enabled, upon operation thereof, to cause the membranes 24 and 25 to be distended back and forth within the chambers 27 and 28 and thereby effect a pumping operation of my novel pump 20, as will be discussed in greater detail presently.

Operation

As previously stated, my novel pump 20 may be used to pump fluids, and is especially well adapted to pump gritty and dirty water, liquids containing sludge, and like liquids, which

have always been considered to be relatively difficult to pump because of the entrained solid matter.

When my pump is to be used for pumping a liquid, a suitable pipe or tube, not shown, may be connected between the source of the liquid and the intake passageway 63, and another suitable pipe or tube, not shown, may be connected to the discharge passageway 62 for discharging the fluid from the pump. Also, for furnishing the power to operate my pump 20, the oil pump 33 is connected by the shaft 221 to a suitable source of power, not shown, such as a motor or the like. After the aforesaid connections have been made operation of my pump 20 is initiated by starting the motor connected to the shaft 221, to thereby drive the oil pump 33.

Assuming that the parts of my pump 20 are in the positions shown in the drawings when operation of my pump 20 is initiated, it will be noted that the oil pump 33, driven by the motor, will take in oil from the reservoir within the housing 22 through the passageways 214, 216, Fig. 2, and will discharge the oil under pressure through the passageways 220 and 198 into the passageway 187 in the actuator valve 35, and from the passageway 187 through a portion of the passageway 179 in the actuator valve 35, and through the passageways 186, 194 and 196 into the chamber 27 inwardly of the distensible membrane 24, thus moving the distensible membrane 24 from the position shown in Figs. 2 and 4 toward the outer side of the chamber 27. At this time the valve head 208 is sealing the passageway 186 from the passageway 185, and the valve head 209 is sealing the passageway 187 from the passageway 188 so that flow of oil through the actuated valve 35 from the passageway 198 is restricted to the passageways 187, 179 and 186.

The valve head 209 being positioned between the passageways 187 and 188 at this time, the chamber 28, inwardly of the distensible membrane 25, is in open communication with the reservoir, in the housing 22 through the passageways 202, 200, 188, 179 and 189 so that any oil in the chamber 28 may be fed into the reservoir upon movement of the distensible membrane 25 inwardly which movement accompanies the aforesaid outward movement of the membrane 24 and the resultant movement of the valve rod 124 as viewed in Fig. 4.

At the start of this movement of the valve rod 124 to the left, it will be noted that the rod 124 is in position to seal the passageway 150 and thereby prevent entrance of oil from the chamber 27 into the passageway 150 through the tube 156. However, the radial groove 173 is aligned with the passageway 163 so that oil may flow under pressure from the chamber 28 through the tube 169, the passageways 163 and 164 in the selector valve 37, the tube 170, and the passageway 190 in the actuator valve 35, into that portion of the passageway 179 to the right of the valve rod 206, as viewed in Fig. 4, to thereby hold the valve rod 206 in position shown in Fig. 4.

As the distensible membrane 24 is moved outwardly toward the cover plate 30 by the pressure of the oil fed by the oil pump 33, any liquid between the cover plate 30 and the membrane 24 is forced out through the passageway 71, lifts the ball 86 off the valve seat 89, and is discharged out through the passageways 59 and 62, the spring 110 and the pressure of the liquid being effective to hold the ball 107 of the intake valve against the valve seat 104 and thereby prevent back-flow

of liquid from the chamber 27 into the intake passageways 60 and 63. Movement of the membrane 24 outwardly causes the rod 124 to move to the left, as viewed in Fig. 4, and thereby causes movement of the membrane 25 inwardly toward the end plate 46. This movement of the membrane 25 causes a partial vacuum within the chamber 28, outwardly of the membrane 25, so that liquid flows in through the inlet passages 63 and 60, unseats the ball 108, and flows through the passageway 75 into the chamber 28, the spring 93 being effective to hold the other ball 87 of the outlet valve against the valve seat 90 to prevent leakage from the chamber 28 into the discharge passageways 62 and 59.

The movement of the valve rod 124 to the left, as viewed in Fig. 4, moves the radial grooves 172 and 173 to the left, out of alignment with the passageways 146 and 163, respectively, and the rod 124 becomes effective to seal all the passageways 150, 146, 159 and 163 through the selector valve 37. As a result, the oil in the passageway 179 to the right of the valve rod 206 in the actuator valve 35, as viewed in Fig. 4, is trapped therein and is effective to hold the valve rod 206 to the left as viewed in Fig. 4.

At substantially the end of the movement of the membranes 24 and 25 and the rod 124 to the left, as viewed in Fig. 4, the radial grooves 172 and 173 in the rod 124 move into alignment with the passageways 150 and 159, respectively. Movement of the radial groove 173 into alignment with the passageway 159 opens the passageway 159 to thereby permit the oil which was trapped in the end portion of the passageway 179, to the right of the valve rod 206 as viewed in Fig. 4, to flow through the passageway 190 in the actuator valve 35, the tube 170, and the passageways 164, 161 and 159 in the selector valve 37, into the reservoir in the housing 22, to thereby release the oil pressure on the right end of the valve rod 206. Movement of the radial groove 172 in the rod 124 into alignment with the passageway 153 opens the passageway 153 and thereby permits oil under pressure within the chamber 27 to flow from the chamber 27 through the tube 156, the passageways 150 and 151 in the selector valve 37, the tube 157, and the passageway 184 in the actuator valve 35, into that portion of the passageway 179 to the left of the valve rod 206, as viewed in Fig. 4, to thereby force the valve rod 206 to the right.

Movement of the valve rod 206 to the right reverses the flow into, and out of, the chambers 27 and 28, that is, a passage is opened from the oil pumps 33 through the passageways 198, 187, 179, 188, 200 and 202 into the chamber 28, and a passage is opened from the chamber 27 through the passageways 196, 194, 186, 179 and 185 back into the reservoir within the housing 22, so that movement of the membranes 24 and 25 and the valve rod 124 is quickly reversed to thereby take liquid in through the passageways 63, 60 and 72 into the chamber 27 and discharge liquid from the chamber 28 through the passageways 74, 59 and 62.

The movement of the valve rod 124 to the right with the membranes 24 and 25 quickly closes the passageways 150, 146, 159 and 163 in the selector valve 37 to thereby trap the oil under pressure in the passageway 179 to the left of the valve rod 206, as viewed in Fig. 4, and to trap the oil under pressure in the chamber 28.

These cycles of operation continue to repeat

first in one direction and then in the other throughout the operation of my pump, and it will be seen that the flow of liquid pumped by my novel pump is substantially continuous.

From the foregoing it will be seen that I have provided a novel membrane pump wherein the membranes thereof may be actuated in a novel and expeditious manner by working fluid fed thereto, under pressure, from a gear-type pump.

Furthermore, it will be noted that the oil pump in my novel membrane pump operates in a closed circuit whereby maximum efficiency may be realized from it.

Also, it will be seen that during the operation of my novel pump the membranes thereof are subjected to little distorting pressure because the pressure of the oil causing the actuation thereof is dependent on the pressure of the liquid being pumped and the differential therebetween is relatively small. Thus, it will be seen that liquid may be pumped by my novel pump at relatively high pressures (the pressures running to several thousand pounds) with little deleterious effect on the membranes of the pump.

In addition it will be seen that the operation of my membrane pump is automatically controlled by mechanism which operates in a novel and expeditious manner.

Further, it will be noted that the flexure of the membranes of my novel pump is relatively slight during the operation of the latter so that the membranes are subjected to very little fatigue stresses.

Also, it will be noted that my novel pump comprises a pleasing appearing, compact and efficient unit which operates smoothly with relatively little vibration.

Hence, while I have illustrated and described the preferred embodiments of my invention, it is to be understood that these are capable of variation and modification and I therefore do not wish to be limited to the precise details set forth, but desire to avail myself of such changes and alterations as fall within the purview of the following claims.

I claim:

1. A pump comprising a housing having two chambers formed therein, two membranes, each of said membranes mounted in a corresponding one of said chambers and extending thereacross, said membranes being distensible in two directions in said chambers, means including a reservoir and a fluid pump for feeding working fluid into said chambers against said membranes to thereby distend said membranes therein, means connected to said chambers for passing liquid into and out of said chambers upon movement of said membranes, valve means for controlling the feeding of said working fluid from said fluid pump to said chambers, and means connected between said membranes for selectively controlling said valve means to thereby effect feeding of working fluid from said fluid pump alternately to one and then the other of said chambers, said last named means including a portion of said housing having two pairs of passageways therein, one of said passageways in each of said pairs being connected to a corresponding one of said chambers and opening into said reservoir for feeding fluid from said chamber to said reservoir, and the other of said passageways in each of said pairs being connected to a corresponding one of said chambers and to said valve means for feeding fluid from said chamber

5 to said valve means, and a slide rod mounted in said portion of said housing and connected to said membranes for movement therewith for selectively opening and closing all of said passageways to thereby control the flow of fluid through all of said passageways from said chambers to said reservoir and said valve means.

2. A pump comprising a housing having a chamber formed therein, inlet and outlet means connected to said chamber, said housing embodying a reservoir adapted to be filled to a predetermined level with a supply of working fluid, a distensible membrane mounted in said chamber, means including a fluid pump mounted within said reservoir in said housing below said predetermined level for feeding working fluid under pressure from said reservoir to said chamber, and means for controlling the flow of said working fluid to said chamber, said last named means including valve means defining passageways connected to said chamber and said reservoir, and a valve rod slidably mounted in said passageways and connected to said membrane for movement therewith, said rod having large and small portions thereon for selectively opening and closing said passageways and controlling the flow of fluid through said passageways during such movement of said rod with said membrane.

3. A pump comprising a housing having two chambers formed therein, means for passing liquid into and out of said chambers, said housing embodying a reservoir adapted to be filled to a predetermined level with a supply of working fluid, distensible membranes in said chambers, means including a gear-type pump mounted within said reservoir in said housing below said predetermined level for feeding working fluid under pressure from said reservoir to said chambers, and valve means for controlling the flow of working fluid from said gear-type pump to said chambers, said valve means being operable to alternately prevent and permit the flow of working fluid from said gear-type pump to one and then the other of said chambers, said valve means including a portion of said housing having a plurality of passageways therein connected to said chambers, and a valve rod slidably mounted in said portion of said housing and connected to said membranes for movement therewith, said rod extending through said passageways and having large and small portions thereon for selectively opening and closing said passageways during such movement of said rod with said membranes.

4. A pump comprising a housing having two chambers formed therein, inlet and outlet means connected to said chambers, said housing embodying a reservoir adapted to hold a supply of working fluid, distensible membranes mounted in said chambers and extending thereacross, means including a working-fluid pump for establishing a closed circuit between said reservoir and said chambers whereby working-fluid may flow from said reservoir to said chambers and back to said reservoir, said working-fluid pump being operable to force working-fluid under pressure through part of said last named means to said chambers to thereby apply pressure to said distensible membranes, and means for selectively controlling the flow of working-fluid through said means for establishing a closed circuit, said means for selectively controlling the flow of working-fluid being operable to direct the flow of

working-fluid from said working-fluid pump alternately to one and then the other of said chambers, said last named means including valve means defining elongated passageways connected between said chambers and said reservoir and working fluid pump, and a valve rod operatively connected to said membranes for movement therewith, said rod extending transversely through said passageways and having means thereon for selectively opening and closing said passageways during such movement of said rod with said membranes.

5. A pump comprising a housing having two chambers formed therein, said housing embodying a reservoir adapted to hold a supply of working-fluid, each of said chambers having a valved inlet passageway and a valved outlet passageway, membranes mounted in said chambers and extending thereacross and being adapted to be distended in two directions therein, means including a fluid pump for establishing a closed circuit for working-fluid between said reservoir and said chambers, said fluid pump being operable to feed working-fluid under pressure through a part of said means to said chambers to thereby apply pressure to said membranes for distending the latter, means including a movable valve member for selectively controlling the flow of working-fluid to said chambers, said last named means being effective when said valve member is disposed in one position to direct the flow of working-fluid from said fluid pump to one of said chambers and when said valve member is disposed in another position to direct the flow of working-fluid from said fluid pump to the other of said chambers, and selector means including a valve rod operatively connected between said membranes in said chambers for selectively controlling the position of said valve member in accordance with the position of said membranes within said chambers.

6. A pump comprising a housing having two chambers formed therein, inlet and outlet means connected to said chambers, two membranes, each of said membranes being mounted in a corresponding one of said chambers and extending thereacross, said membranes being distensible in two directions in said chambers, means including a fluid pump for feeding working-fluid under pressure into each of said chambers on one side of the membrane therein for distending said membranes toward the other side of said chambers, a connecting member interconnecting said membranes, said connecting member being movable with said membranes and operable to impart distending movement to each of said membranes upon distending movement of the other of said membranes, a movably mounted valve member associated with said second named means for selectively controlling the flow of working fluid from said pump to said chambers, said valve member being adapted when disposed in one position to direct the flow of working-fluid from said fluid pump to one of said chambers and when disposed in another position to direct the flow of working-fluid from said fluid pump to the other of said chambers, and a valve unit connected to said chambers for feeding working-fluid to said valve member to position the latter, said valve unit including said connecting member, and said connecting member being movably mounted in said valve unit and being operable upon movement with said membranes to open and close said valve unit in accordance with the position of

said membranes and to thereby control the feeding of fluid to said valve member and thereby control the position of said valve member.

7. A pump comprising a housing having two chambers formed therein, two membranes, each of said membranes being mounted in a corresponding one of said chambers and extending thereacross, said membranes being distensible back and forth within said chambers, a connecting member interconnecting said membranes, and reciprocable therewith upon distensible movement of said membranes back and forth within said chambers, liquid inlet and outlet means opening into said chambers on one side of the membranes therein, means including a fluid pump for alternately feeding working-fluid under pressure into one and then the other of said chambers on the other side of said membranes to thereby alternately distend one of said membranes and then the other toward said one side of said chambers, and valve means for controlling the operation of said last named means, said valve means being operable to alternately vent first one and then the other of said chambers on said other side of said membranes to the interior of said housing to thereby relieve the pressure of the working-fluid fed by said pump into said chambers, said connecting member being slidably mounted in said valve means and being effective to control the operation of said valve means in timed relation to the movement of said membranes and thereby being effective to control the venting of said chambers to said housing, and to control said means for feeding working-fluid, in timed relation to the movement of said membranes.

8. A pump comprising a housing having two chambers formed therein, two membranes, each of said membranes being mounted in a corresponding one of said chambers and extending thereacross, said membranes being distensible in said chambers in inward and outward directions relative to said housing, a connecting member interconnecting said membranes to thereby effect inward distending movement of each of said membranes during outward distending movement of the other of said membranes and outward distending movement of each of said membranes during inward distending movement of the other of said membranes, liquid inlet and outlet means opening into said chambers outwardly of said membranes, means including a fluid pump for feeding working-fluid under pressure into said chambers inwardly of said membranes to effect distention of said membranes outwardly, an actuator valve connected to said fluid pump, said actuator valve including a valve rod movably mounted therein, said actuator valve being operable when said rod is disposed in one position to selectively direct working fluid from said fluid pump to one of said chambers to thereby effect outward distention of the membrane in said one chamber, and said actuator valve being operable when said valve rod is disposed in another position to selectively direct working-fluid from said fluid pump to the other of said chambers to thereby effect outward distention of the membrane in said other chamber, and a selector valve operatively interconnecting said chambers inwardly of said membranes with said actuator valve and the interior of said housing for feeding working-fluid from said chambers to said actuator valve to thereby move said valve rod back and forth between said one position and said other position and for venting said chamber to the in-

terior of said housing, said selector valve including said connecting member and said connecting member being operable to control the operation of said selector valve in accordance with the position of one of said membranes whereby when said one membrane is in full inwardly distended position said selector valve is effective to selectively direct working-fluid to said actuator valve to thereby move said valve rod to said one position and when said one membrane is in full outwardly distended position said selector valve is effective to selectively direct working-fluid to said actuator valve to thereby move said valve rod to said other position.

9. A pump comprising a housing having two chambers formed therein, two membranes, each of said membranes being mounted in a corresponding one of said chambers and extending thereacross, said membranes being distensible in two directions in said chambers, means including a fluid pump for feeding working-fluid under pressure into each of said chambers on one side of the membrane therein for distending said membranes toward the other side of said chambers, a movably mounted valve member connected to said means for controlling the flow of working-fluid from said pump to said chambers, said valve member being adapted when disposed in one position to direct the flow of working-fluid from said pump to one of said chambers and when disposed in another position to direct the flow of working-fluid from said pump to the other

5 of said chambers, and a valve unit mounted between said chambers and connected thereto for feeding working-fluid to said valve member to position the latter, said valve unit including an elongated member movably mounted therein and having two opposite end portions each operatively connected to a respective one of said membranes, said elongated member being movable with said membranes upon distending movement 10 of the latter, and said elongated member being operable upon movement of said membranes to selectively open and close said valve unit in accordance with the position of said membranes and to thereby control the position of said valve 15 member.

LINDSAY H. BROWNE.
